2 SHEETS-SHEET 2.

UNITED STATES PATENT OFFICE.

EUGENE G. BURKS AND NEENIAN HAYES, OF BIRMINGHAM, ALABAMA.

COAL-WASHING APPARATUS.

1,132,433.

Specification of Letters Patent. Patented Mar. 16, 1915.

Application filed July 3, 1914. Serial No. 848,985.

To all whom it may concern:

Be it known that we, EUGENE G. BURKS and NEENIAN HAYES, citizens of the United States, residing at Birmingham, in the county of Jefferson and State of Alabama, have invented certain new and useful Improvements in Coal-Washing Apparatus; and we do hereby declare the following to be a full, clear, and exact description of the invention, such as will enable others skilled in the art to which it appertains to make and use the same.

The present invention relates to coal washing apparatus, and consists more particularly of an apparatus for recovering values held in suspension in the wash water with which the coal, ores and the like are treated to cleanse the same.

The present invention further relates to apparatus of the type set forth in our allowed application Serial No. 795,302, filed October 15, 1913, entitled "coal washing apparatus"; and it is to be understood that the present apparatus may be employed to 20 replace the apparatus described in our above prior application, and receive the wash water directly from the jigs or other apparatus; or the same may be used in conjunction with our prior construction to receive the wash water therefrom and subject the same to a further treatment to recover such values as remain suspended in the wash water.

It is an object of the present invention to provide an apparatus of the above character wherein wash water may be introduced to the settling tank at a variety of different points, in order to prevent uneven deposit of the material in the tank out of the path of the elevator by which the same is removed.

Another object of the invention consists in providing apparatus as above indicated, wherein the wash water is introduced in a manner to prevent undue agitation of the liquid in the settling tank, and thereby prevent interference with the progress of the deposition.

A further object of the invention resides in providing in the settling apparatus a stand-pipe provided with a series of valve-controlled outlets through which the clear liquid above the deposit may be successively drawn off and utilized over again in the jigs or other apparatus, or discharged into the usual stream where the same is carried away.

With these and other objects in view the invention consists in the novel details of

construction and combinations of parts more fully hereinafter disclosed and particularly pointed out in the claims.

In the accompanying drawings forming a part of this application, and in which similar reference symbols indicate corresponding parts in the several views: Figure 1 is a top plan view of an apparatus made in accordance with the present invention. Fig. 2 is a central vertical section of the same. Fig. 3 is a sectional view taken on the line 3-3 of Fig. 1, parts being broken away. Fig. 4 is a sectional view of a detail; and Fig. 5 is an end elevation of the same taken at right angles to Fig. 4.

Referring more particularly to the drawings, wherein one embodiment of the apparatus is illustrated, 1 and 2 designate, respectively, side and end walls assembled on a bottom 3 to constitute a tank which is suitably mounted on a supporting structure 4. The walls 1 and 2 are preferably inclined, as shown, to form a hopper-shaped tank, in which the wash water is introduced and permitted to remain until the material in suspension has been deposited to the bottom thereof, whence the same is removed continuously or from time to time, as required, by a suitable elevator 5, here shown to be of the endless conveyer type.

Projecting from opposite side walls 1 of the tank are a pair of partitions 6 and 7, extending parallel and in proximity to one end wall 2, and forming with the same a pair of inlet compartments 8 and 9. Each compartment 8 and 9 is provided with a pair or more of inclined baffle plates 10 and 11, projecting in staggered relation, respectively, from the respective partitions 6 and 7 and the end wall 2 of the tank.

The wash water is conveyed to the settling tank by means of a sluice-way 12, extending across the tank and arranged above the inlet chambers 8 and 9. The sluice-way 12 is provided with a plurality of discharges, here shown to be three in number, the end discharges 13 and 14 of which are preferably arranged adjacent each opposite side wall 1, and are provided each with a spout 15 and 16 to direct the wash water into the compartments 8 and 9, respectively. Passage of wash water through the discharges is controlled by means of gates or other suitable valves 17 and 18, which may be provided with suitable operating means.

A central discharge 19, controlled by a

suitable gate 20, is arranged to connect with an apron 21 extending approximately to the center of the settling tank, and may be provided with a bottom formed of a downwardly inclined portion 22, terminating in a portion 23 upwardly inclined therefrom. The inclination 22 induces flow of the wash water into the apron 21 when the gate 20 is opened and the end portion 23 is 10 arranged to check the force of the wash water before delivering the same to a vertical zigzag trough. The zigzag trough is composed of two sections 24 and 25, secured together substantially at right angles, and 15 supported between the inner ends of the partitions 6 and 7 and the adjacent end wall 2 of the tank.

As disclosed to advantage in Fig. 2, the section 24 is provided with a vertically-disposed end 26, and the bottom of the trough is arranged to provide a constricted channel with the end portion 23 of the apron, whereby the wash water may be prevented from entering the settling tank in too great 25 volume. The section 25 is, as shown, preferably relatively short, and terminates substantially centrally of the tank above the elevator 5.

A stand-pipe is erected in the settling tank to one side of the elevator, as shown, and the same is built up of a number of sections 27, provided each, at opposite ends, with meeting flanges 28, whereby the same may be secured together to form the stand-pipe. Each section 27 of the stand-pipe is provided, preferably centrally thereof, with a right angularly disposed inlet 29, faced off to provide a seat against which a flap valve 30 is arranged to close.

As disclosed to better advantage in Figs. 4 and 5, each flap valve 30 is pivoted to a collar 31, clamped about each section 27 of the stand-pipe, and arranged to be operated by rods or valve stems 32 mounted for a reciprocating movement in the partition 6 and end wall 2. Each rod 32 has its inner end received and pivoted between a pair of ears 32' projecting from each of the valves 30. By moving the rods 32 the valves 30 may be opened when desired, and the liquid drained off through the stand-pipe. It is to be understood that we do not limit ourselves to the connection shown in Figs. 4 and 5, as any suitable connection may be 55 employed between the valve rods 32 and the valves 30.

In operation the wash water, either directly from the jigs, or from apparatus similar to that set out in our prior application, is conveyed by means of the sluice-way 12 to the settling tank, into which the same is introduced generally through the central discharge 19 in a volume controllable through the gate 20. The wash water passing 65 through the discharge 19 enters the

apron 21, where increased flow is induced by the downwardly inclining portion 22. This flow is, however, checked by the upwardly inclined end 23, the latter directly delivering the wash water to the section 24 of the zigzag trough. Flowing down between the bottom wall of the section 24 and the end 23 of the apron, in a reduced volume, the wash water impinges against the extended bottom of the trough-section 25, where the force of the same is again broken, and from which point the wash water flows down the relatively short section 25 into the settling tank, where it is received with a minimum disturbance to the surrounding liquid.

It has been found that where the wash water is introduced continuously at one point, the deposit at the bottom of the tank is affected thereby to collect unevenly at the bottom of the tank, and in some cases out of the path of the elevator. In order to overcome this disadvantage, it is desirable, from time to time, to change the inlet of the wash water, and to this end the valve 20 may be closed, and either or both valves 17 and 18 may be opened to permit the wash water to pass out through the discharges 13 and 14, whence the same is delivered over the spouts 15 and 16 to the inlet chambers 8 and 9, respectively. The wash water flowing from the spouts 15 is directed against the upper portion of the respective partition, and is directed therefrom down to the baffle plate 10, which, in turn, directs the liquid against the end wall 2 of the tank. In further descent the water encounters the inclined baffle plates 11, whereby it is directed against the lower end of the partitions, the baffle plates 11 and the partition forming a constricted passage, through which the liquid issues in a relatively quiet stream and passes beneath the lower edge of the same and into the settling tank.

When it is desired to clean the settling tank, the valves 17, 18 and 20 may be closed to prevent further entrance of the wash water, and after sufficient time has elapsed for a thorough precipitation of all suspended matter, the valve 33, at the highest elevation on the stand-pipe, may be opened by drawing the respective rod 32 outwardly. The clear liquid thereupon passes through the outlet 29 and down through the stand-pipe, by which the same may be conveyed to a reservoir for re-use, or may be directed into the usual stream. When the level in the settling tank has been reduced below that of the highest valve, the next in series may be operated in a similar manner, and similarly the other valves may be operated in succession to drain off the clear liquid above the deposit, which is then removed, as far as possible, by means of the elevator 5. The tank is then flushed in the usual way and otherwise cleaned.

It is obvious that those skilled in the art may vary the details of construction and arrangement of parts without departing from the spirit of our invention, and therefore we do not wish to be limited to such features except as may be required by the claims.

We claim:

1. In an apparatus for recovering values from wash water, the combination of a settling tank, a partition mounted in said tank and providing an inlet chamber therein, a tortuous trough arranged in said settling tank to one side of said partition, a sluice-way for conveying wash water extending above said tank, and a plurality of discharges leading from said sluice-way and arranged to deliver the wash water one to said inlet chamber and another to said tortuous trough, substantially as described.
2. In an apparatus for recovering values from wash water, the combination of a settling tank, a partition mounted in said settling tank and providing an inlet compartment therein, a plurality of baffle plates arranged in staggered relation in said inlet chamber, a tortuous trough arranged in said tank to one side of said inlet compartment, a sluice-way for conveying wash water, and a plurality of discharges leading from said sluice-way and arranged to deliver the wash water one to said inlet compartment and one to the tortuous trough, substantially as described.
3. In an apparatus for recovering values from wash water, the combination of a settling tank, a pair of partitions mounted in said tank and providing a pair of adjoining inlet compartments, a tortuous trough arranged in said tank between said inlet chambers, a sluice-way for conveying wash water extending across said tank and arranged above said inlet chambers, and a plurality

of discharges leading from said sluice-way and arranged to deliver wash water one for each of said inlet chambers and one for said tortuous trough, substantially as described.

4. In an apparatus for recovering values from wash water, the combination of a settling tank, a partition mounted in said settling tank and providing an inlet compartment therein, a tortuous trough mounted in said settling tank to one side of said partition, a sluice-way for conveying wash water, a plurality of discharges leading from said sluice-way and arranged to deliver the wash water to said inlet compartments and said tortuous trough, a stand-pipe erected in said tank and provided with a series of outlets, and valves for controlling the passage of wash water to said outlets, substantially as described.

5. In an apparatus for recovering values from wash water, the combination of a settling tank, a stand-pipe erected in said settling tank and provided with a plurality of outlets arranged at different elevations, valves for controlling the passage of wash water to said outlets, a pair of partitions mounted in said settling tank and providing a pair of adjoining inlet compartments therein, a tortuous trough mounted between said compartments, a sluice-way for conveying wash water, and a plurality of discharges leading from said sluice-way and arranged to deliver wash water one to each of said inlet compartments and one to said tortuous trough, substantially as described.

In testimony whereof, we affix our signatures, in presence of two witnesses.
